DEVIATION RECORDING DEVICE

Albert H. Beal, Houston, Tex.

Application August 21, 1944, Serial No. 550,441

2 Claims. (Cl. 33—205.5)

1

This invention relates to a deviation recording apparatus.

An object of the invention is to provide apparatus of the character described designed to be lowered into a well bore and containing means which are maintained inoperative while the apparatus is being lowered but which becomes active when the apparatus reaches the selected place in the bore, and is maintained stationary at such location, whereby a record is made of the inclination of the bore at the selected point.

In drilling a well bore it is desirable to maintain the same as nearly straight as possible, for well known reasons, and in order to do this it is necessary, from time to time, to survey the bore in order to obtain the required deviation data so that correction can be made in case deviation occurs. The invention herein disclosed has been particularly designed for the purpose of ascertaining the inclination, if any, of the well bore at a selected point therein so that the bore can be straightened at the point of deviation, if deviation occurs. The invention also embodies a novel timing arrangement for maintaining the record making means inoperative, or inactive, while the apparatus is being lowered to the point where the survey is to be made and which, after a predetermined interval, becomes operative to actuate the record making means to make a record of the deviation.

With the above and other objects in view the invention has particular relation to certain novel features of construction, operation and arrangement of parts, an example of which is given in this specification and illustrated in the accompanying drawing wherein—

Figure 1 shows a fragmentary, vertical, sectional view showing the upper end of the apparatus.

Figure 2 shows a fragmentary, vertical, sectional view showing an intermediate portion thereof.

Figure 3 shows a fragmentary, side, elevational view of the timing device gearing; and

Figure 4 shows a side elevation of the apparatus, partly in section, as mounted in the housing, said housing being shown in section.

Referring now more particularly to the drawing wherein like numerals of reference designate the same parts in each of the figures, the numeral 1 designates an elongated, tubular housing shaped to be lowered into a well. The upper end of this housing is closed by a cap 2 to which the lower end of the cable 3 is connected. The cable is used

2

for lowering the apparatus into, and withdrawing it from the well.

Attached to the lower end of the housing there is a guide point 4 having a deep socket 5 therein in which is located the coil spring 6.

Enclosed within the housing there is a cylindrical casing which is formed of upper, intermediate and lower sections 7, 8 and 9, the sections 7 and 8 being connected by an inside coupling 10. The upper end of the casing is closed by a cap 11 having a stuffing box 12 therein and the lower end 13 of the casing is closed as shown in Figure 2 and is seated on the upper end of the coil spring 6, which forms a shock absorber as shown in Figure 4.

The coupling 10 is inwardly thickened and has an axial bearing 14 therethrough through which the driving rod 15 is slidably fitted and this rod is surrounded by the stuffing box 12a carried by the coupling 10. The upper end of this rod extends upwardly through the stuffing box 12 and carries the enlarged head 16.

Fixed on the rod 15 within the housing there is an enlarged spring seat 17 and surrounding 25 said rod and interposed between said seat and the cap 11 there is a strong coil spring 18.

Above the coupling 10 the rod 15 is formed with a rack face 19.

Fixed on the upper end of the coupling 10 and 30 upstanding therefrom there is a frame having the side members 20, 20 whose upper ends are connected by the head 21 through which the rod 15 passes. The timing device gearing is mounted in this frame. This gearing includes a spur gear 22 which is in constant mesh with the face 19 and which is fixed on the transverse shaft 23. Fixed on the shaft 23 there is a large spur gear 24 which is in mesh with a smaller spur gear 25 fixed on one end of the cross shaft 26. Loosely 35 mounted on the other end of the shaft 26 there is a spur gear 27 which is adjacent a ratchet wheel 28 which is fixed on the shaft 26. Pivoted on the gear 27 there are the pawls 29, 29 which are spring pressed and which are arranged to co- 40 operate with the ratchet wheel 28. When the rod 15 is pulled upwardly to place the spring 18 under compression the shaft 26 will be rotated through the gears 22, 24 and 25 but the ratchet wheel 28 will be rotated in the direction of the arrow in Figure 3 and no rotation will be imparted to the spur gear wheel 27 nor to the smaller gear 30 which is in mesh therewith.

Upon release of the rod 15 the spring 18 will cause the same to move downwardly thus reversing 45 the rotation of the gearing above referred to 50 55

and causing the ratchet wheel 28 to engage the pawls 29 to impart rotation to the gear wheel 27 and to the gear 30 in mesh therewith. This gear 30 is fixed on the transverse shaft 31 and rotates a train of gearing therebeneath designated generally the numeral 32. This train of gearing embodies also a conventional escapement 33 which is controlled by a swinging pendulum 34 which is fixed on the transverse shaft 35. Therefore, when the rod 15 is released it will not suddenly move downwardly but its downward movement will be controlled by the timing gearing hereinabove described.

The numeral 35 designates a cross head which is attached to the lower end of the rod 15 and depending from this cross head there is a tubular skirt 36.

A preferred form of recording mechanism has been illustrated and will now be described; there is a tubular anchor 36 slidably fitted into the upper end of the lower section 9 of the casing and provided with a longitudinal slot 37. A key 38 is anchored to the section 9 and extended inwardly into the slot. This anchor is supported on a coil spring 39 which is fitted within the section 9 and which is supported on inwardly extended pins 40 which are anchored to the casing.

The upper end of the anchor 36 is enlarged and fitted closely within the intermediate section 8 of the casing providing a downwardly facing external stop 41 which limits the downward movement of the anchor. Said anchor is normally held in its upper position by the coil spring 39.

There is a disklike record receiving element 42 whose margin is suitably attached to the upper end of the anchor 36. This record receiving element is preferably, though not necessarily, transparent and is formed of any suitable material adapted for the purpose. Preferably it is slightly flexible and of sufficient softness to receive a mark or impression and will not be liable to be broken or mutilated.

Spaced beneath the pins 40 are the inwardly extended pins 43 which support a ring 44. Supported on this ring there is a coil spring 45 which supports a plate 46 and normally holds it against the pins 40. This plate 46 has a central opening 47 and surrounding said opening on the plate there is an annular seat 49 on which the ball 50 is mounted. This ball is retained in place by the retainer plate 51 which is secured on the plate 46. The retainer plate 51 has a central opening and a post 52 is attached to, and upstands from, the ball 50 through said opening and its upward end is pointed and spaced beneath the recording element 42.

An externally threaded stem 53 depends from the ball 50 through the opening 47 and a pendulum is attached to and depends from said stem. This pendulum includes a head 54 and a weight 55. This weight encloses a coil spring 56 whose upper end is connected to the head and whose lower end is connected to the weight. This pendulum maintains the pointed post 52 in vertical position. The head and weight have a ball and socket joint connection 57 whereby the shock of the lateral swing of the pendulum will be absorbed to prevent breakage or bending of parts, particularly when the pointed end of the post 52 is engaged with the record receiving element 42. Depending from the cross head 35 there is an upper pendulum 58 which is located within the skirt 36. The lower end of this upper pendulum is provided with a pointed marker 59. The upper end of the pendulum 58 is formed with a

spherical head 60 forming a ball joint member which is normally supported in the socket 61 formed in the upper face of the bearing plate 62 which is secured to the lower end of the cross head 35. The lower end of this cross head has a deep vertical socket 63 in which there is located a bearing block 64 and a coil spring 65 is enclosed within the socket 63 and presses downwardly against the ball joint member 60 and maintains it firmly seated in the socket 61. The pressure of the bearing block 64 against the joint member 60 is sufficient to prevent vibration or any undue oscillation of the pendulum 58 but permits said pendulum to assume a true vertical position.

In use the rod 15 is pulled upwardly the required distance depending on the depth at which the survey is to be made thus placing the spring 18 under compression. The apparatus is then enclosed in the housing 1 and the cap 2 attached thereto and the apparatus is then lowered into the well. As above stated when the rod 15 is pulled upwardly the ratchet 28 will rotate idly thus allowing the free upward movement of said rod.

Upon release of the rod 15 the timing mechanism will immediately begin to operate and the rod 15 will begin a slow downward movement, said movement being controlled by the timing mechanism. The rod is initially drawn upwardly far enough to allow sufficient time for lowering the apparatus to the point where the survey is to be made before the recording means operates. When the apparatus has reached the desired location in the well it should be held there stationary to allow sufficient time for the pendulum 58 to move downwardly until the pointed marker 59 engages and forms a mark on the record receiving element 42. The spring 65 will thereafter yield to prevent the marker from unduly mutilating the record receiving element.

The downward movement of the rod 15 and cross head 35 continues until the lower end of the skirt 36 comes into contact with and moves the record receiving element 42 downwardly into engagement with the pointed upper end of the post 52, placing the spring 39 under compression and said posts will make a mark on the under side of said receiving element and thereafter the spring 45 will yield to prevent undue mutilation of the record receiving element by said post.

The springs 65, 39 and 45 will yield sufficiently to prevent the record receiving element 42 from being unduly mutilated but at the same time have sufficient resistance to cause said markers to make visible marks on the record receiving element.

When the apparatus is lowered to the desired place in the well where a record of the inclination is to be made, a sufficient time should be allowed to lapse to give the timing device time to operate to make the record and the apparatus may then be withdrawn for an inspection of the record receiving element.

If the markers 52, 59, make marks exactly at the center of the element 42 it will be known that the well bore was exactly vertical at the point where the record was made.

If the marks made on the record receiving element are off center they will be on opposite sides of the center of the receiving element. The distance the marks so made are from the center of the receiving element indicates the amount of inclination of the bore. In other words the data furnished by the marks made by the markers 52, 59 are sufficient to enable the amount and direction of the inclination of the bore at a point where

the record is made to be readily ascertained and if the inclination of the bore at that point makes it necessary, the bore can be straightened in any approved manner.

What I claim is:

1. In a deviation recording device shaped to be lowered into a well and including a casing having upper and lower sections and an inside coupling connecting said sections and also having means in the lower section effective, upon operation thereof, to make a record of the inclination of a well bore, a cap closing the upper end of the upper section, said cap and coupling having aligned bearings, a rod slidable through said bearings and having its upper end extended above the cap and forming a grip, said rod having a rack face thereon, a spring seat on the rod, a coil spring around the rod between said seat and cap provided to force the rod downwardly, when the spring is placed under compression, to operate the record making means and gearing in the casing forming a timing device and geared to the rack face to retard the downward movement of the rod.

2. In a deviation recording device shaped to be lowered into a well and including a casing having upper and lower sections and an inside coupling connecting said sections and also having means in the lower section effective, upon operation thereof, to make a record of the inclination of a well bore, a closure for the upper end of the upper section, said closure and coupling having aligned bearings, a rod having a rack face and slidable through said bearings and having its upper end extended above the closure and forming a grip whereby the rod may be manually moved in one direction, a spring seat on the rod, a coil spring around the rod between said seat and closure arranged to be placed under compression when the rod is so moved and provided to force the rod in the other direction, when the spring is placed under compression, to operate the record making means and a gearing assembly in the casing and supported on the coupling and forming a timing device and geared to the rack face to retard the downward movement of the rod.
